UNITED STATES PATENT OFFICE.

OTIS T. CRAFTS, OF MANCHESTER, NEW HAMPSHIRE.

HEEL BASE AND RUBBER HEEL.

Application filed November 5, 1927. Serial No. 231,252.

My present invention relates to heel bases for use in conjunction with rubber heels, and includes a novel combination of heel base and rubber heel, as well as a novel process of manufacturing and assembling same, including also a novel rubber heel.

Various methods of manufacturing heel bases without the use of a separate rand have been clearly set forth in my prior 10 issued Patents No. 1,458,524, June 12, 1923, and No. 1,528,912, March 10, 1925, and in carrying out my present invention I preferably utilize the methods set forth in said 15 patents, and hereby refer to them for further details.

One of the principal functions of a heel base for use in conjunction with a rubber heel is for the external appearance of same, since a heel base, of leather or the like, presents a much neater appearance than a whole 20 rubber heel with no base between the heel and the heel seat of the shoe. Therefore, an important object of the present invention is the provision of a heel base for attachment to rubber heels, which will have all the 25 advantages incident to the external appearance thereof, but which will be more economical to construct, will be more flexible, and will also be more comfortable to the 30 wearer.

The broad principle of the present invention is the provision of a heel base composed of a plurality of U-shaped layers, one surface of said base having formed therein a rand-like rim, and the inner edges of said 35 layers defining an open central and breast portion. Being thus open, across the breast and central portion of the base, it will be obvious that greater flexibility will be obtained, which degree of flexibility has not 40 been possible in prior heel bases due to the fact that at least one of the layers composing said bases was closed across the central and breast portion. Due to the saving in stock 45 required, a great economy will be effected in the construction of these heel bases, which economy will be further increased by the fact that I may utilize, instead of whole, 50 expensive, U-shaped lifts or layers, half sections, or pieced sections of any size, and whether of undistorted material or not. Even though made of such small, pieced 55 sections, and of material which would otherwise be considered as waste, my heel base is capable of taking edge finishes, burnishings,

inkings, etc., fully as well as a heel base composed of whole lifts or expensive pieces.

With the central and breast portions of the base thus open, it becomes necessary to 60 compensate for at least the breast portion of the base, to prevent the entrance of water, snow, or other foreign substances at this point, and to this end I have devised the 65 novel rubber heel illustrated herein, wherein means are provided to occupy the breast portion of the base, or if desired, both the breast and central portions. This means preferably consists in an upraised plug or 70 lug, either of the same material as the rubber heel itself, or of a material having a greater degree of resiliency and cushioning 75 than the rubber heel. This upstanding plug is preferably of a height as great as the highest inside edge of heel base to be utilized. If a heel base having a thinner inside edge is utilized, or one lower than the height of the plug, the consistency of the 80 material of which the plug is formed will permit cushioning and depression thereof, so that there will be no lumps or other uncomfortable protuberances on the heel. By thus having the plug of a height equal to the highest inner edge of base to be combined 85 therewith, a rubber heel of this type may be made standard, the only variations being those now practiced for size of heels, etc. 90 The cost of the addition of this plug to a rubber heel will be far exceeded by the saving in material effected by my novel heel bases herein described.

Preferably also, these bases and rubber 95 heels will be assembled as a unit, before attachment to a shoe, but it will be appreciated that I am not thus limited, but may attach the parts of the unit separately to the shoe if desired.

I may also, if desired, construct a heel base composed of a plurality of superimposed rands, such as counter rands, 100 or the like. Such a base would of course come under the broad scope of this present invention, comprising as it does a plurality of U-shaped layers having a randlike rim in one surface of said base. However, in a base of this type, there would be an excessive heel-seat-engaging cup, due to the relative thinness of the inner edges of the rands when built up to the desired outside 105 edge or finished height. In order to counteract this excessive cup, I construct the 110

rubber heel to compensate therefor, as by providing the rubber heel with a convex base-contacting face, the convexity of the heel being such that it will compensate for the excessive cup in the base, and will also extend into the open central and breast portions of the base, thus filling these open portions of the base to the desired extent.

Also, if desired, I may utilize a separate insert, of leather, leatherboard, or the like, formed with a suitable convexity to perform the above function. It may also be desirable to utilize, in conjunction with the convex face of the heel, a protruding plug of rubber, either of the same or a different consistency as the rubber heel itself, this plug performing the same function as the plug on the heel first above described.

Several variations of the broad principle above described are possible, and some of same are illustrated herein, but I believe that all of these modifications and variations come within the broad scope of the present invention, and have therefore included the same herein.

The above and further objects of the invention, details of construction, advantages and combinations will be hereinafter more fully pointed out and claimed.

Referring to the drawings, illustrating preferred embodiments of the present invention,

Fig. 1 is a perspective view of the heel base of the present invention;

Fig. 2 is a perspective of a rubber heel constructed to cooperate with the base of Fig. 1;

Fig. 3 is a perspective of the combined base and heel;

Fig. 4 is a cross-sectional view illustrating the united base and heel ready for application to the heel seat of a shoe;

Fig. 5 is a cross-sectional view of a modification of rubber heel;

Fig. 6 is a perspective of a rubber heel with means to occupy the breast portion only of the base;

Fig. 7 is a perspective of a rand;

Fig. 8 is a cross-sectional view illustrating a base constructed of the rands of Fig. 7 and combined with a rubber heel for attachment to the heel seat of a shoe;

Fig. 9 is a perspective view of the rubber heel illustrated in Fig. 8;

Fig. 10 is a cross-sectional view of a modification of rubber heel with base attached thereto;

Fig. 11 is a cross-sectional view of a further modification of heel; and

Fig. 12 is a cross-sectional view of a still further modification of rubber heel.

In carrying out my invention, and as shown in the drawings, I construct the heel base 1 of two layers, 2 and 3. The showing of the two layers is for illustrative purposes

only, since I may utilize as many layers as are requisite to complete or build a heel base having the necessary outside or edge height. One of these layers, here shown as layer 3, has a randlike rim 4 formed therein, of a concavity suitable for application to the heel seat of a shoe on which the base is to be utilized. I have shown, in Fig. 1, the heel base constructed of pieced sections, of undistorted material, the lower layer 2 being united approximately centrally of the rear of the base, and the upper layer 3 having an uninterrupted rear portion, the sections being united at the sides, as clearly shown. However, within the range of this invention it is immaterial what number of pieces or sections are utilized, it being feasible to construct the base 1 of two whole U-shaped pieces, if desired. The inner edges of the U-shaped layers 2 and 3, as will be noted, define an open central and breast portion 5, which construction represents a marked step forward in this art, prior heel bases having the central and breast portions closed by one or more layers of the base. By so forming these heel bases, viz., with open central and breast portions, I obtain a heel base of great flexibility, and one which will readily adapt itself to the heel seat of the shoe to which it is to be applied. In addition to the advantages of flexibility, is the further advantage of economy, the savings effected by omitting the central and breast portions being considerable.

The heel base 1 may be manufactured in any desirable way, as for example by the processes set forth in my two prior patents above mentioned, or the layer 3 may have the concavity formed therein before application thereof to the layer 2, I not being limited to any set method of manufacture.

It will be readily apparent that the heel base of Fig. 1 will have all the external or edge appearance, as well as across a portion of the breast, of a heel base formed of complete layers, as previously.

With the advent of the base above described, however, I find that it is necessary to provide means, preferably on the rubber heel joined with the base, to compensate for the space defined by the inner edges of the U-shaped layers. This means may occupy the breast portion only of the base, or may occupy both the breast portion and the central portion. To this end I have devised a novel rubber heel 6 having thereon, as shown in Fig. 2, a plug 7, of a shape adapted to fill the entire space defined in the U-shaped base. This plug 7 may be of the same material as the rest of the rubber heel, as shown in Figs. 2, 3 and 4, or it may be composed of a material of different consistency, as shown at 8 in Fig. 5 on the heel 9. The plug 8 may consist of crepe rubber or

any material of different consistency than the main portion of the rubber heel, but preferably having greater cushioning capacity than said heel. In Figs. 3 and 4 I have illustrated the heel base 1 having its inner edge 10 of less height than the plug 7, the outside edge 11 being the height desired for attachment to the particular heel seat here illustrated as 12. This is for illustrative purposes only, and clearly illustrates the plug 7 projecting above the inner edge of the heel base, and of a height equal to the height of the highest inner edge of heel base to be combined therewith. However, on application of the united heel and base to the heel seat 12, the pressure exerted by the heel nailing and other machines, as well as by the wearer of the shoe, will depress the projecting portion of the plug 7 so that it will not be noticeable or uncomfortable to the wearer. For this reason it will be seen that a plug 7 of greater cushioning capacity than the rest of the rubber heel will be most desirable.

The plane surface 13 of the rubber heel 6, surrounding the plug 7, forms a seat for the top or plane surface of the base 1, effecting a neat union between the heel and base.

The plug 7 also, it will be appreciated, will provide a seat for the foot of the wearer throughout the entire extent of the heel and base. Should it be desired, however, to leave the central portion of the base open, I provide a heel 14 having a plug 15 thereon, which plug corresponds to the plugs 7 and 8 so far as the breast portion of the base is concerned, but which plug 15 will not extend into the central portion of the base, leaving the same open, and creating a vacuum effect, or air cushion, which, in certain types of shoes will be desirable.

The united heels and bases, as above described, will be possessed of greater flexibility than prior units, because of the open central and breast portions defined by the inner edges of the base layers, and for this reason the units will lend themselves with greater ease to proper attachment to the heel seats of shoes, rendering this attaching operation more simple and efficient because of this flexibility.

The heel base illustrated in Fig. 8 will be possessed of all the features and advantages of the base above described, in that it is inexpensive to manufacture, flexible, and will have a heel-seat-engaging cup pre-formed therein. This heel base, designated generally as 17 consists of a plurality of rands 18. These rands may be formed from counter skivings, box toe skivings, or may be the usual crimped rand if desired. A plurality of these rands 18, having an outside edge 19 of predetermined height, are secured to-

gether, as by adhering, either before or after crimping, and are then compressed or molded to desired contour, and will have a cup 20 in one face of the base of a concavity suitable for attachment to the heel seat 21.

In a base of this type, however, due to the relative thinness of the inner edge 22, there will be a cup on the surface opposite the cup 20, and in order to compensate for this extra or excessive cup, I have devised the novel rubber heel illustrated at 23, forming the base-engaging side of the heel with a convex surface 24. This convex surface, as shown in Fig. 8, will compensate for the cup in the under surface of the base 17, by providing an even seat for the base, and the central and breast portions of the convex surface will occupy the central and breast portions of the base, thus assuring an even seat for the heel seat of the shoe and the heel of the wearer.

The heel base and heel above briefly described are obviously within the range of the present invention, which embraces a U-shaped heel base, and means on the rubber heel to occupy the breast, or breast and central portions of the base.

In Fig. 10 I have illustrated the heel base 17 and a rubber heel 25 having its surface convexed toward the central and breast portions for a predetermined distance, as shown at 26, and instead of carrying this convexity entirely across the surface of the heel, I apply, in this form, a plug 27, of crepe rubber or other material preferably of greater cushioning capacity than the rest of the rubber heel, which plug will be of a size and shape to fill or occupy the breast portion of the base, and the central portion also if desired. Said plug 27 also is of a height equivalent to the greatest inside edge height of any base to be utilized in conjunction with this form of heel. Crepe rubber I have found to be the most desirable substance for this plug 27, but I am not limited thereto, and may utilize any substance of a cushioning nature which will be applicable in this position.

In Fig. 11 I have illustrated a further slight modification, wherein the base 17 is utilized in conjunction with a rubber heel 28, having a convex member 29 between the rubber heel 28 and the base 17. This member may be of leatherboard, fibreboard, or any desirable substance, and may be either affixed to the rubber heel 28, or may be inserted as a separate member between the base and the heel. This form of structure will be found desirable in certain types of shoes, and is obviously included in the scope of the present invention.

In Fig. 12 is illustrated a still further modification wherein the rubber heel 30 has its convex portion 31 formed of crepe rubber

or other material of a greater cushioning capacity and resilience than the heel portion 30. This member 31 is preferably molded with the rubber heel 30 as an integral part thereof, and its function will be the same as the heels above described, except for the greater cushioning effect afforded by the entire layer 31 of soft material.

Either of the heels 23, 25 or 30 could be utilized with equal ease and efficiency with the heel base 1, if desired, since the pressure of the heel nailing and other machine operations, and the weight of the wearer would be sufficient to depress the convex surface of the heel which would be beneath the U-shaped layer 2.

I believe that the heel bases above described are novel, and have therefore claimed the same broadly in the present application, as well as the forms of heels illustrated herein, and have also claimed the combined units as a part of the present invention, as well as the methods of manufacturing and assembling same.

While I have necessarily described my present invention somewhat in detail, it will be appreciated that I may vary the size, shape and arrangement of parts within reasonably wide limits without departing from the spirit of the invention.

My invention is further described and defined in the form of claims as follows:

1. A combined heel base and rubber heel, said base comprising a plurality of U-shaped layers defining open central and breast portions, a rand-like rim on one surface of said base, and means on said rubber heel to occupy the breast portion of said base, said means comprising a raised portion on said heel of a height as great as the highest inner edge of any base to be utilized therewith.

2. A combined heel base and rubber heel, said base comprising a plurality of U-shaped layers defining open central and breast portions, a rand-like rim on one surface of said base, and means on said rubber heel to occupy the breast portion of said base, said means comprising a raised portion on said heel of greater cushioning capacity than the rest of said heel.

3. A combined heel base and rubber heel, said base comprising a plurality of U-shaped layers defining open central and

breast portions, a rand-like rim on one surface of said base, and means on said rubber heel to occupy the breast portion of said base, said means comprising a raised portion on said heel of greater cushioning capacity than the rest of said heel and of a height as great as the highest inner edge of any base to be utilized therewith.

4. A combined heel base and rubber heel, said base comprising a plurality of U-shaped rands defining open central and breast portions, a rand-like rim on one surface of said base, and a convex base-engaging surface on said rubber heel extending into said open central and breast portions.

5. A combined heel base and rubber heel, said base comprising a plurality of U-shaped rands defining open central and breast portions, a rand-like rim on one surface of said base, a convex surface on said heel to compensate for the excessive cup in said base, and means projecting upwardly from said convex surface to occupy the open central and breast portions of said base.

6. A combined heel base and rubber heel, said base comprising a plurality of U-shaped rands defining open central and breast portions, a rand-like rim on one surface of said base, a convex surface on said heel to compensate for the excessive cup in said base, and means projecting upwardly from said convex surface to occupy the open central and breast portions of said base, said means being of greater cushioning capacity than the tread portion of said rubber heel.

7. A combined heel base and rubber heel, said base comprising a plurality of U-shaped rands defining open central and breast portions, a rand-like rim on one surface of said base, and a convex base-engaging surface on said rubber heel extending into said open central and breast portions, the portion of said rubber heel forming said convex base-engaging surface being of greater cushioning capacity than the tread portion of said rubber heel, whereby pressure on said heel will compress said softer portion to desired shape.

In testimony whereof, I have signed my name to this specification.

OTIS T. CRAFTS.
